INVENTOR:

Abraham Block,
BY
Everett Cook, ATTORNEYS.

UNITED STATES PATENT OFFICE.

ABRAHAM BLOCK, OF BLOOMFIELD, NEW JERSEY.

SAFETY POCKET.

Application filed December 22, 1923. Serial No. 682,157.

To all whom it may concern:

Be it known that I, ABRAHAM BLOCK, a citizen of the United States, and a resident of Bloomfield, in the county of Essex and State of New Jersey, have invented certain new and useful Improvements in Safety Pockets, of which the following is a specification.

The objects of this invention are to ~~10~~ cure an improved safety pocket which shall render it impossible for a pickpocket to remove the contents without attracting the attention of the wearer; to insure that any attempt to pick the pocket of its contents ~~15~~ shall attract the attention of the wearer; to combine with a closed compartment and an open compartment from which the pickpocket can feel the contents, so that he will attempt to pull the pocket inside out, special ~~20~~ means for causing such a pull to be felt by the wearer; to provide a simple and practical construction for securing such results, and to obtain other advantages and results as may be brought out by the following ~~25~~ description.

Referring to the accompanying drawings, in which like numerals of reference indicate the same parts throughout the several views,

Figure 1 is an outside view of the upper ~~30~~ part of a pair of trousers having side and hip pockets embodying my invention;

Figure 2 is an inside view of the same;

Figure 3 is a front view of such trousers upon a wearer and partly broken away to ~~35~~ show the pull of attempting to turn a side pocket inside out;

Figure 4 is a similar view from the rear illustrating the pull of attempting to turn a hip pocket inside out;

Figure 5 is a detail section horizontally through the upright edge of the side pocket next to the fly of the trousers, looking from the front;

Figure 6 is a similar section of the hip pocket, on line 6—6, Figure 2;

Figure 7 is a horizontal cross-section of the side pocket, with the closed compartment open;

Figure 8 is a similar cross-section with ~~50~~ said closed compartment shut, and

Figure 9 is a vertical cross-section through the hip pocket, with the closed compartment open.

In the specific embodiment of the invention shown in said drawings, 1 indicates a pair of trousers having a side pocket 2 with

a median partition 3 in its plane dividing the pocket into compartments 4 and 5, said partition being thin enough so that a pocket-book 6 or other valuable in one compartment can be plainly felt by a hand inserted in the other compartment. One compartment is provided with concealed means for closing the entrance to it, while the other compartment is left open so that a hand ~~60~~ may be readily inserted into it. Obviously either compartment may be the open one and the other the closed one, but in the present drawings I have shown the inner compartment 4, next the wearer, open and the other one 5 closed. Furthermore, any suitable means known to the art may be used at the entrance to the closed compartment for covering and concealing it, but for illustration I have shown, see Figures ~~65~~ 7 and 8, the side of the partition 3 next the closed compartment 5 provided at the mouth of said compartment with a flap 7 and cooperating separable fasteners such as snap member 8, 9 and button and button-hole 10, 11 for releasably securing it to the outer wall 12 of the pocket. Another flap 13 secured to the edge of said outer wall 12 is provided to fold inwardly over the margin of the partition 3 and be secured thereto as ~~70~~ by snap members 14, 15. This covers and conceals the entrance to the compartment 5, while leaving the entrance to the other compartment 4 open and easily entered by the hand.

The edge of the side pocket 2 is according to my invention connected to the crotch of the trousers, preferably to the seam 16 thereat, and preferably it is the lower part of the pocket which is thus connected. This ~~75~~ may be done in any suitable way, but I have shown it accomplished, see Figure 2, more especially, by continuing the outer wall 12 of the pocket to that portion of the seam 16 at which the fly 17 is located, as a connecting web 18. While this connecting web is shown as extending from the lower end of the pocket 2 all the way to its top, it is obvious that it could extend any desired distance upward from said lower end, without ~~80~~ affecting its function of causing a pull up on the crotch of the trousers when any attempt is made to turn the pocket inside out.

It will be understood that in using my invention the pocket book 6 or other valuable ~~110~~ is placed in the closed compartment 5, as shown in Figure 3, so that if a pickpocket

inserts his hand into the other, or open compartment 4 he can plainly feel the contents of the closed compartment, through the partition 3, but cannot draw it from the pocket; he therefore resorts to an attempt to turn the whole pocket inside out, so as to then cut it and release the contents, and such attempt is what causes the pull upon the attachment of the bottom part of the pocket to the crotch of the trousers, as clearly illustrated in Figure 3, and attracts the attention of the wearer. The attempt of the pickpocket is thus frustrated by the use of my invention, and the contents of the pocket saved.

My invention is just as applicable to a hip pocket as to a side pocket, and such an application is also illustrated in the drawings, the reference numeral 20 indicating a hip pocket which has a middle partition 21, see Figure 9, dividing it into outer and inner compartments 22, 23, the outer one having an interior closing flap 24 and an exterior closing flap 25 both like those already described and by which the outer compartment can be securely closed and concealed. The usual pocket flap 26 is shown provided for the entire pocket, as is usual, but this has no effectiveness in closing the open compartment 23 against pickpockets. The lower end of the hip pocket 20 is connected as by a strip 27 to the crotch seam 16 of the trousers, and the operation of it in pulling upon said seam to attract the attention of the wearer when a pickpocket attempts to turn the hip pocket inside out is exactly the same as already described in connection with the side pocket 2. Obviously, both of the

hip pockets of a pair of trousers can be connected to the crotch seam if desired, as I have indicated in Figure 4, and both side pockets can be constructed like the one I have shown and described.

Obviously my improved pocket can be applied to other garments than trousers, and various modifications or changes can be made in the detail construction of the invention without departing from the spirit and scope thereof. Therefore I do not desire to be understood as limiting myself except as required by the following claims when construed in the light of the prior art.

Having thus described the invention, what I claim is:

1. In a garment, the combination of a pocket having one end secured to said garment adjacent its mouth, a secret compartment directly associated with the pocket and so arranged that its contents may be felt therefrom, and a connection from the other end of said pocket to a portion of the garment to pull upon the wearer when an attempt is made to turn the pocket inside out.

2. In a garment, the combination of a pocket having one end secured to said garment adjacent its mouth, said pocket having an open compartment and a secret closed compartment coextensive therewith and so arranged that its contents may be felt from the open compartment, and a connection from the other end of said pocket to a portion of the garment to pull upon the wearer when an attempt is made to turn the pocket inside out.

ABRAHAM BLOCK.
